UNITED STATES PATENT OFFICE.

EDGAR M. BENHAM, OF NORWOOD, OHIO, ASSIGNOR TO THE MOSLER LOCK COMPANY,
OF COVINGTON, KENTUCKY, A CORPORATION OF OHIO.

CHANGEABLE-COMBINATION KEY LOCK.

Application filed January 21, 1925. Serial No. 3,718.

To all whom it may concern:

Be it known that I, EDGAR M. BENHAM, a citizen of the United States, residing at Norwood, in the county of Hamilton and State of Ohio, have invented certain new and useful Improvements in Changeable-Combination Key Locks, of which the following is a specification.

My invention relates to locks, and more particularly to locks of the type commonly known as changeable combination key locks, and this invention relates specifically to an improvement of the lock which is the subject-matter of an application filed by me April 26, 1922, Serial No. 556,709, and entitled Changeable combination key locks.

In said prior and copending application I have described a lock having a plurality of commonly pivoted tumblers, some having pivotal movement in opposite direction to other tumblers. These tumblers are divided into three sets, to wit, the main tumblers, which dog fingers on slides adjustably carried on the bolt bar, the guard tumblers, which dog fingers on plates also supported on the bolt bar, and change tumblers, which dog fingers on other plates also mounted on the bolt bar. The slides and plates above mentioned are preferably arranged in a stack, with a spacer plate intermediate each two of these elements, these spacer plates also extending between adjacent tumblers.

One of the principal objects of my invention is to simplify and cheapen the construction above referred to without detracting from the advantages thereof. More particularly, the object of this invention is to eliminate the necessity of providing spacer plates in addition to the members which cooperate with the tumblers.

Other objects of my invention will be in part obvious and in part pointed out hereinafter.

In accordance with my invention, I provide slides for dogging the main tumblers. Intermediate each two slides I interpose a plate, which also preferably extends between two adjacent main tumblers. Some of these plates are arranged to cooperate with guard tumblers, and others of these plates are arranged to cooperate with change tumblers. In this way, each of these plates not only acts as a spacer plate for the

slides and main tumblers, but also serves as an operative part of the guard and change mechanism of the lock.

In order that a clearer understanding of my invention may be had, attention is hereby directed to the accompanying drawings, forming a part of this application and illustrating one possible embodiment of my invention.

Referring to the drawings:

Fig. 1 is a top view of the lock;

Fig. 2 is a top view of the lock with the cover removed;

Fig. 3 is a sectional view and is taken on the line 3—3 of Fig. 1;

Fig. 4 is a diagrammatical view, showing the position of a main tumbler, the slide and bolt when the lock is unlocked in the regular way;

Fig. 5 is a diagrammatical view, showing the position of a guard tumbler adjusted into unlocking position, and a cooperating plate carried on the bolt bar, which is shown in locked position;

Fig. 6 is a diagrammatical view showing a change tumbler adjusted into unlocking position, and a cooperating plate carried on the bolt bar, which is shown retracted to such an extent that the regular key may be withdrawn from the lock while the lock is in unlocked condition;

Fig. 7 is a plan view of a regular key;

Fig. 8 is a plan view of a guard key; and

Fig. 9 is a plan view of a change key.

Similar reference characters refer to similar parts throughout the several views of the drawings.

Referring to the drawings, the lock mechanism is housed in a suitable casing, comprising a box 1, having a cover 2. The lock mechanism includes a suitable bolt bar 3, having a bolt portion 4. The bolt bar is provided with two pins 5, on which are nested or stacked the slides 6 for the main tumblers 7, the plates 8 for the guard tumblers 9, and the plates 10 for the change tumblers 11. There are a plurality of slides 6 and an equal number of main tumblers 7. Between each two of the slides 6 is interposed either one of the plates 8 or one of the plates 10, and each of these plates extends inwardly a sufficient distance to have its inner end at all times disposed between

two adjacent main tumblers 7. In this way, each main tumbler 7 is maintained at all times in alignment with its corresponding slide 6. The tumbler sets 7, 9 and 11 are preferably, but not necessarily, commonly pivoted on a single pin 12, extending upwardly from the base of the casing 1. The number of guard tumblers and the number of change tumblers may be varied arbitrarily, and, if desired, the change tumblers may be omitted entirely. The only requirement is that for each guard tumbler there is a corresponding guard plate 8, and that for each change tumbler 11 there is a corresponding change plate 10. The tumblers may assume various shapes. For instance, each regular tumbler may be U-shaped, pivoted at its rear, and have a recess 13 at its front adapted to receive the finger 14 of the corresponding slide 6 when the tumbler has been aligned therewith, by means of manipulating the regular key 15 in the key tube 16 in the regular way, and after the guard tumblers have been properly set up by means of the guard key. Each guard tumbler 9 may be rectangular in shape, with a cut-away portion 17 around the key tube 16, and have a rearwardly projecting finger or shoulder portion 18 for engagement by a guard key 19 operating in key tube 20, and at its front may be provided with a forwardly projecting finger 21 adapted to enter recess 22 in the corresponding guard plate 8 when the tumbler has been properly adjusted by means of the guard key 19. Each change tumbler 11 may be similar to the guard tumblers 9, or, if desired, instead of providing a finger at its front, as on the guard tumblers, the front edge of each tumbler 11 may be provided with a recess 23 adapted to receive a finger 24 on the corresponding change plate 10; so that when the change tumblers have been adjusted by properly manipulating the change key 25 in the key tube 20, the recesses 23 of the change tumblers 11 are aligned with the fingers 24 of the change plates 10 to permit sufficient retraction of the bolt, by means of the regular key 15, to permit this regular key to be removed from the lock while the lock is in unlocked condition.

As illustrated in the drawings, there are eight main tumblers 7 and eight slides, one cooperating with each main tumbler. As before stated, intermediate each of these tumblers is either a guard tumbler or a change tumbler. Accordingly, the total number of guard and change tumblers are seven in the lock illustrated. There are four guard tumblers and three change tumblers, and these guard and change tumblers are disposed in alternating succession. Accordingly, there are eight bits 26 on the regular key, in addition to the bit 27, which engages the

bolt bar to slide the same, and four bits 28 in the guard key, and three bits 29 on the change key.

The operation of a lock of this type being well-known, it is not deemed necessary nor proper to describe the operation thereof, it being sufficient to say that this lock operates in the manner usual to locks of this type.

In the lock of my said prior application, the presence of the spacer plates between the slides and tumbler plates necessitated the inclusion of corresponding spacer plates between the tumblers. These spacer plates between the tumblers are now eliminated. Accordingly, for a given number of tumblers the thickness of the lock is now reduced by an amount equal to the aggregate thickness of the spacer plates which were required heretofore and are now eliminated as separate elements. Conversely, and for the same reason, in a lock of a given thickness more tumblers can be accommodated in my improved lock, and more changes of combination are available. The decrease in the number of parts for a given number of tumblers decreases cost of materials and manufacture, as well as decreasing the time and expense of assembly. All the advantages of my prior lock construction are retained, and the manner of operating, adjusting and re-setting the lock is similar to the manner of operating, adjusting and re-setting said prior lock.

What I claim is:—

1. In a lock of the character described, the combination with a first tumbler and a second tumbler adjacent thereto, of a bolt bar, and a plate carried on the bolt bar in alignment with the second tumbler and in overlapping relation with said first tumbler.

2. In a lock of the character described, the combination with a first tumbler and a second tumbler adjacent thereto, of a bolt bar, and a plate carried on the bolt bar in alignment with the second tumbler and in overlapping relation with said first tumbler, said second tumbler and plate having a recess and tongue cooperation and relatively adjustable into and out of dogging relation with each other.

3. In a lock of the character described, the combination with a first tumbler and a second tumbler adjacent thereto, of a bolt bar, and a plate carried on the bolt bar in alignment with the second tumbler and in overlapping relation with said first tumbler, said plate having a recess at its rear edge and said second tumbler having a forwardly extending finger, said second tumbler being adjustable to align said finger with said recess.

4. In a lock of the character described, the combination with a first tumbler and a second tumbler adjacent thereto, of a bolt bar, and a plate carried on the bolt bar in align-

- ment with the second tumbler and in overlapping relation with said first tumbler, said plate having a finger projecting rearwardly from its rear edge and said second tumbler 5 having a recess on its front edge, said second tumbler being adjustable to align said recess with said finger.
5. In a lock of the character described, the combination with a slidable bolt bar and a plurality of tumblers, of plates carried on said bolt bar and extending between said tumblers in alternating relation therewith, and other tumblers cooperating singly with each of said plates. 10
- 15 6. In a lock of the character described, the combination with a slidable bolt bar and a plurality of tumblers, of plates carried on said bolt bar and extending between said tumblers in alternating relation therewith, 20 and other tumblers cooperating singly with each of said plates, a plurality of slides mounted on said bolt bar and each cooperating individually with one of said tumblers first mentioned, said plates being disposed between said slides in alternating relation therewith.
- 25 7. In a lock of the character described, the combination with a slidable bolt bar and a
- plurality of tumblers, of plates carried on said bolt bar and extending between said tumblers in alternating relation therewith, and other tumblers cooperating singly with each of said plates, at least one of said plates being a guard plate and at least one of said plates being a change plate. 30
- 35 8. In a lock of the character described, in combination, a plurality of tumblers stacked one directly upon another, a plurality of members aligned singly with said tumblers and coacting therewith, and means for holding alternate tumblers stationary while the other tumblers are actuated. 40
- 45 9. In a lock of the character described, in combination, a plurality of tumblers stacked one directly upon another, a plurality of members aligned singly with said tumblers and coacting therewith, said members being stacked one directly upon another, and means, comprising alternate ones of said members, for holding alternate tumblers stationary while the others of said tumblers are actuated. 50

This specification signed this 12 day of January, 1925.

EDGAR M. BENHAM.
